UNITED STATES PATENT OFFICE

2,594,634

DISPENSER FOR LIGHT-SENSITIZED SHEETS

Charles F. Galloway, Los Angeles, Calif.

Application November 25, 1949, Serial No. 129,427

2 Claims. (Cl. 312—54)

1

The present invention relates to a dispenser of the type adapted to hold and progressively dispense single sheets of sensitized paper.

The present invention has for an object a device wherein sensitized paper in sheet-form may be dispensed from the said container, a sheet at a time, with assurance that light will not enter the container and spoil other sensitized sheets therein during a dispensing operation.

A further object is the provision of a dispenser, which may be quickly loaded with sensitized paper.

Further objects include the provision of a dispenser which is inexpensive in cost of manufacture, slightly in appearance, fool-proof in operation, and generally superior to devices now known to the inventor.

In the drawing:

Figure 1 is a perspective view of the dispenser,
Figure 2 is a top plan view of the container,

Figure 3 is a bottom plan view of the cover for the container, and

Figure 4 is a transverse sectional view on the line 4—4 of Figure 1.

Referring now with particularity to the drawing, the improved dispenser includes a container 1 provided with a cover 2. The container 1 is of the form shown in cross-section in Figure 4 and has a front wall 3, rear wall 4, and end walls 5 and 6 with the base 7 of said container provided with an elongated transversely arcuate slot 8 adjacent the front wall 3 of said container and with an inclined wall or table portion 9 extending from the rear wall to the arcuate groove 8. As shown, the end walls 5 and 6 are substantially of uniform height. The rear wall 4 and end walls 5 and 6 are formed with an elongated external groove 10. A portion of said end walls 5 and 6 and front wall 3 is grooved at 11 and 12. In addition, the top edge of the front wall 3 is longitudinally recessed between the end walls 5 and 6, as shown at 13.

The cover 2 is provided with a curved top wall 14, a front wall 15 and two end walls 16 and 17. The construction is such that the end walls are of lesser depth than the depth of the front wall and do not entirely bound the curved top wall. In other words, the curved top wall rearwardly of the front wall portion extends beyond the end walls as shown in the figures. This extension or skirting, here designated as 18 for the curved top wall, overlaps the rear edge 19 of the end walls 5 and 6, and said portion 18 is provided on its inner surface with a longitudinally extending bead 20 adapted to be received within the longitudinal groove 10 of the container. The front wall of

the cover has a skirting 21 provided with a longitudinally extending bead 22 which fits between and within the grooves 11 and 12. The construction is such that the skirting 18 of the cover flexes 5 so as to allow the beads 20 and 22 to be received within the grooves 10, 11 and 12 of the container and thereby hold the cover securely, but detachably, to the container. As shown in the drawing and particularly in Figure 1, there is a close fit 10 engagement between the ends of the cover and the ends of the container. The front wall 15 of the cover 2 is thickened with respect to the remaining portion of the cover to give stability to the structure and likewise to accommodate other 15 elements of the invention. As shown in Figure 4, the bead portion 22 of the cover is spaced by a groove 23 from a portion 24. Portion 24 carries a pair of seals 25 and 26. Seal 25 is secured to a flattened edge of portion 24 while seal 26 is carried 20 at an angle to seal 25.

Adapted to be longitudinally positioned for rotation within the container and within the 25 confines of the groove 8 is a roller 27. This roller is mounted on end trunnions fitted within the ends of the container and one trunnion externally carries a knob 28 whereby the roller may be 30 manually turned. As shown, the periphery of this roller is adjacent the seal 25 and the lower edge of seal 26 engages the roller. With the cover in position on the container, a slot is 35 formed as between the bead 21 and the recess 13. The seals 25 and 26 are spaced rearwardly of the said discharge slot so that when the roller is turned, a sheet may be fed by the roller between said seals and outwardly through said slot.

As illustrated in Figure 4, the table 9 is at an angle to the base. A stack of sensitized paper rests partly upon the table 9 and partly upon the 40 roller 27, rearwardly of the seals 25 and 26. The lowermost sheet of the stack is at all times in pressure engagement with the periphery of the roller, there being a pair of spring fingers 28 and 29 secured at one of their ends to the wall 4 of the container, while the opposite ends are 45 secured to an elongated pad 31. The pad 31 is adapted to engage the outermost sheet of the said stack of sensitized paper as shown in Figure 4 at 32. Both fingers are bowed as illustrated in Figure 4.

50 The operation, uses and advantages of the invention just described are as follows:

The container is loaded with a stack of light-sensitized paper in a dark room and the cover then secured to the container. This cover by 55 having a resilient skirt 18 will retain its position

on the container without shifting and release thereof from the container requires some exertion on the part of the operator to flex the skirt.

When a stack of the light-sensitized sheets is to be dispensed one at a time, the lowermost sheet will engage the friction roller 27, and as the roller is turned, the lowermost sheet will be fed between the light seals 25 and 26 and outwardly through the discharge slot in the front wall of the container. As shown, the lowermost sheet is forced to bend in passing over the periphery of the roller between the light seals 25 and 26 and likewise to bend slightly in being directed through the discharge slot. We observe that the seal 26 is rearwardly of the discharge slot and has elongated edge engaging the periphery of the roller. Such a seal forms an obstruction to the passage of light within the container. When the lowermost sheet of light-sensitized paper is moved by the roller, a seal 26 will flex and engage the top surface of said sheet and still obstruct any light passage within the container. This construction provides a convenient form of light trap.

It is to be observed that the stack of light-sensitized sheets has a concave appearance as indicated in Figure 4. The spring fingers tend to depress the stack so that the lowermost sheet of said stack will at all times be in frictional engagement with the roller. The table 9 is at an angle and as the stack is pressed downwardly by the said fingers, such as may occur when the stack is reduced as to thickness, the table will nevertheless support the stack and hold the lowermost sheet in frictional engagement with the roller. This is an important feature of the present construction.

I claim:

1. A device for dispensing single sheets of light-sensitized paper including: a container, a cover for said container, said container provided with an elongated curved groove, a feed roller within said groove; said container formed with a discharge slot forwardly of the said roller, an inclined table portion within said container and

10

rearwardly of said roller, said table and said roller adapted to support therebetween a stack of sensitized paper, the said roller positioning one edge of the stack above the discharge slot, means

5 at all times urging the lowermost sheet of said sensitized paper into engagement with the periphery of said roller, and a flexible light seal member carried by the cover and engaging the periphery of the roller rearwardly of the discharge slot and below the edge of the stack supported by the roller.

2. A dispenser for sheets of light-sensitized paper comprising: a container, a cover for detachable engagement with said container, said cover and said container provided with a portion therebetween defining a discharge slot, said container formed with an elongated arcuate groove, a roller within said groove and rearwardly of said discharge slot, means for supporting a stack 15 of light-sensitized sheets between the periphery of the roller and container, the said roller positioning one edge of the stack above the discharge slot, spring fingers engaging the top of said stack of light-sensitized sheets for urging the lowermost sheet of said stack into frictional engagement with the roller, and a flexible light seal carried by the cover and engaging the periphery of the roller forwardly of and below the edge of the stack of light-sensitized sheets supported by 20 the roller.
